UNITED STATES PATENT OFFICE.

NICOLAS TORNAUW, OF ST. PETERSBURG, RUSSIA.

PREPARING MAPS, DRAWINGS, &c.

SPECIFICATION forming part of Letters Patent No. 655,813, dated August 14, 1900.

Application filed November 13, 1899. Serial No. 736,871. (No specimens.)

To all whom it may concern:

Be it known that I, NICOLAS TORNAUW, a subject of the Emperor of Russia, and a resident of St. Petersburg, Russia, have invented 5 certain new and useful Improvements in Preparing Maps, Drawings, and the Like, of which the following is a specification.

This invention consists of a process whereby geographical and other maps, drawings, 10 or similar articles intended for purposes of instruction, information, or study (whether printed, photographed, or drawn by hand) are rendered better suited for the purpose by being prepared in such a manner that drawings or marks with chalk, charcoal, crayon, 15 or the like may be made thereon and afterward be effaced without any damage to the surface of the map or the like.

Attempts have been made to render maps, 20 and more particularly geographical maps, suitable for the purpose for which this invention has been devised, but none of them have proved successful, mainly for the reason that their original delineations could not be preserved intact for any length of time.

Now by this invention not only is the original map or print protected from destruction, but its durability is increased, and existing maps, plans, pictures, or the like may be treated 30 by the improved process in the following manner:

The sheet having the map, plan, picture, or the like printed or drawn thereon is impregnated with any suitable waterproofing 35 media—such, for example, as what is known as “Enduit pégamoid,” but any other known waterproofing agent may be used, provided it does not impair or injure the paper or the printed or otherwise-delineated matter there- 40 on. The map after being made impervious to moisture is covered with a thin layer of some transparent and water-resisting adhesive substance. It has been found by experience that the varnish known under the 45 name of “Mordant 14 N. extra fort” is pre-eminently suited for the purpose; but any other suitable varnish may be employed. Before this varnish or coating has had time to dry the surface of the map is by means 50 of a suitable sieve or sifter sprinkled with

finely-powdered pumice-stone, emery, or other suitable roughening-powder. This powder becomes embedded in the adhesive layer and by so doing produces a transparent coating of a roughness sufficient to enable the map 55 to be drawn upon or marked with chalk or the like. When the surface has become dry, the map or the like is ready for use.

The foregoing is a description of the treatment to which an existing map or the like is 60 to be subjected, and the process may be similarly applied with such modifications of detail as the nature of the article may necessitate to other maps, plans, pictures, or the like, including globes, employed for purposes 65 of tuition, study, or information.

Where the object is to produce new maps, pictures, or drawings with the advantages hereinbefore described, the paper, canvas, or other material to be used for the purpose 70 may be waterproofed before the map or picture is drawn or printed thereon; but the adhesive substance and the powdered pumice-stone or the like must in all cases be applied after the production of the drawing or print. 75

As before stated, the process is applicable to a vast variety of articles employed for purposes of teaching, study, or reference, it being particularly suitable for ordnance and school maps, though it may also be used with 80 great advantage for anatomical plates, working or key plans, drawings of machinery, (whether used for tuition or for purposes of construction,) globes, and the like, and the process will also prove extremely serviceable 85 in preparing maps of ephemeral interest, such as war maps, plans of fortifications, &c.

Having now particularly described and ascertained the nature of this invention and in what manner the same is to be performed, 90 I declare that what I claim is—

1. The process substantially as hereinbefore described of treating maps, drawings and the like for the purpose specified, which consists in waterproofing the same, covering 95 the same with a transparent adhesive substance, and applying a finely-powdered hard substance thereto.

2. The process substantially as hereinbefore described of treating maps, drawings 100

and the like for the purpose specified, which consists in printing the map, drawing or the like upon the proper material, waterproofing said material, covering the same with a transparent adhesive substance, and sprinkling on the adhesive substance while moist a finely-powdered hard substance.

In testimony whereof I have signed my name to this specification in the presence of two subscribing witnesses.

NICOLAS TORMAUW.

Witnesses:

KARL PREIZ,
FRANZ HASSLACHER.
